(57) **ABSTRACT**

A smoking device for generating and releasing smoking vapor free from contamination into the mouth of a user comprising a mouthpiece for providing vapor for inhalation to a user including a tubular casing containing a heater for heating a smoking substance at a substantially constant low temperature by regulating the flow of fuel by a thermal regulator and further having means for visual indication of the operation of the device.

SYSTEMS AND METHODS FOR
AEROSOLIZING A VAPORIZABLE
MATERIAL

CROSS-REFERENCE

This application is a national phase application, filed under 35 U.S.C. § 371, of PCT International Patent Application No. PCT/US2015/031152, filed May 15, 2015, which claims the benefit of U.S. Provisional Patent Application Ser. No. 61/994,787 filed May 16, 2014, the disclosures of all of which are incorporated herein by reference in their entirety.

BACKGROUND

Smoking devices, such as cigarette holders and pipes are well known in the art for providing flavored vapor from a smokeable substance to a user for therapeutic and smoking pleasure. However, existing devices used have no control of heating and combustion of the tobacco products. The devices tend to produce toxic, tarry and carcinogenic by-products which are harmful and also impart a bitter and burnt taste to a mouth of a user.

A further problem is that there is no control of contamination of the inhaled vapor mixture with heater exhaust gases, due to inappropriate proportioning and location of the inlets and the exhaust vents. Typically, the exhaust gas is used to directly heat the tobacco, and those gases contain harmful byproducts of incomplete combustion.

In an effort to overcome these deficiencies, there is a need for providing a device structure and substance for producing vapor for smoking which is free from harmful by-product and provides a cool and soothing vapor for smoking.

SUMMARY

The present invention is directed to improvements in smoking devices, particularly to smoking articles which employ a formed smokeable material cartridge as a source of producing vapor by heat transfer to the cartridge by conduction, convection and/or radiation for smoke and flavor. The present invention relates to self-contained vaporization devices, and more particularly, to a low-temperature vaporization device for use with tobacco, botanicals or other smokeable products. The device is of an elongated main body with a mouthpiece at one end and an attached tubular casing at the other end having a vaporization chamber and a heater. The mouthpiece and the casing form a unitary unit. The device can be portable.

The present invention is drawn to a novel smoking device consisting of a mouthpiece and a casing having a heater, a low temperature vaporization chamber, a fuel tank, an igniter with control means for maintaining equilibrium point by keeping the operating temperature below about 400 F. In some examples, the operating temperature is below 350 about F. In order to maintain a stable operating temperature, a thermal regulator can be used to control flow rate of the fuel.

Further provided herein is a mouthpiece made of a high temperature food-safe material, such as ceramic, glass, or high temperature plastics known as PEI resin (brand name Ultem). However, suitable plastic or wood, etc., can also be used but may additionally require an insulating material to prevent excessive heat reaching the user's lips.

Additionally, air inlets are directed downwards, so that fresh ambient air drawn through mixes with the vapor

2

generated into the vaporization chamber located above the smokeable substance cartridge, which is extracted from the cartridge by inlets located below the cartridge and drawn into user's mouth for inhalation.

5 It is another object of the invention to provide air inlet or inlets having a diameter and direction sized to admit ambient air into the chamber to heat up the substance and not effect the operating temperature and also regulating the velocity of ambient air entering and mixing with the vapor generated 10 heating in the chamber at such a rate that the proportionate inhalation passage provides a perception to the user as if the smoke is drawn through a cigarette.

It is still another object of the invention to provide a heater which is separated from the vapor chamber by an insulating 15 medium such as ring made of PTFE, ceramic or other insulating material and thereby preventing the exhaust gases produced by the heater from entering and contaminating the vapor in the vaporization chamber collected for inhalation.

Another object of the invention provides a heater formed 20 of a conductive shell and a catalyst. The shell may be of one or more material formed by welding or pressing together. The catalyst can be of platinum or palladium impregnated metal or glass or other suitable material, which provides for efficient flameless combustion of the fuel and glows red 25 when heated to indicate that the device is activated. Additionally, a feedback loop can be employed to regulate the desired temperature.

In some implementations, the smokeable material cartridge may be formed and shaped for easier insertion into the 30 heating chamber and to snugly fit into the cavity of the heating chamber for improved thermal conduction and vaporization. The cartridges may be formed and wrapped into a wrapper. In some implementations, the smokeable material may be provided in a loose form in a pouch. The 35 wrappers and pouches may be formed of a material which does not produce significant amount of harmful gases.

An aspect of the present disclosure relates to a cartridge 40 fitted in a device, the cartridge comprising a permeable pouch containing a smokeable material, wherein the device is configured to heat the smokeable material in the permeable pouch, and wherein the permeable pouch allows an exit of a vapor generated from the heating of the smokeable material.

Additional aspects and advantages of the present disclosure 45 will become readily apparent to those skilled in this art from the following detailed description, wherein only illustrative embodiments of the present disclosure are shown and described. As will be realized, the present disclosure is capable of other and different embodiments, and its several 50 details are capable of modifications in various obvious respects, all without departing from the disclosure. Accordingly, the drawings and description are to be regarded as illustrative in nature, and not as restrictive.

INCORPORATION BY REFERENCE

All publications, patents, and patent applications mentioned in this specification are herein incorporated by reference to the same extent as if each individual publication, 60 patent, or patent application was specifically and individually indicated to be incorporated by reference.

BRIEF DESCRIPTION OF DRAWINGS

65 The novel features of the invention are set forth with particularity in the appended claims. A better understanding of the features and advantages of the present invention will

be obtained by reference to the following detailed description that sets forth illustrative embodiments, in which the principles of the invention are utilized, and the accompanying drawings or figures (also "FIG." and "FIGS." herein), of which:

FIG. 1 is a side view of a vaporization device.

FIG. 2 is a sectional view of the vaporization device in FIG. 1.

FIG. 3 is a perspective view of a heater.

FIG. 4 is a cutaway view of an alternate vaporization device.

FIG. 5 is a sectional detail view of a cartridge.

FIG. 6 is a perspective view of a cartridge.

FIG. 7 is a sectional detail view of a cartridge.

FIG. 8 is a sectional detail view of a cartridge.

FIG. 9 is an example of a pouch in a vaporization device.

FIG. 10 is an example of an oven chamber of a device.

DETAILED DESCRIPTION

Referring to FIG. 1 and FIG. 2, the exterior of the device 10 comprises a mouthpiece 11, a tubular case 12, and the base 14 of a butane tank 21. The mouthpiece is removable and creates an airtight seal with the interior of the case. With the mouthpiece removed, a cartridge (FIG. 5) is introduced to vaporization chamber 15 of a heater 16. The mouthpiece is then reinserted to close the device.

The mouthpiece is made of a high-temperature and food-safe material such as ceramic, glass, or various high-temperature plastics such as PEI resin (brand name Ultem). Design is simplified by use of high temperature materials, but standard plastics or wood, etc, can also be used with the addition of an insulating component that prevents any excessive heat from reaching the user's lips.

To activate the device, the butane tank is pulled axially outward, partially removing it from the case. This starts the flow of butane by opening a master valve 18, and then activating a piezoelectric igniter 13. The tank remains in the partially removed position for the duration of use. While the master valve is open, butane flows through a thermal regulator 17, and into the carburetor 20. Ambient air enters the case through slot 19. A venturi in the carburetor entrains air, causing it to mix with the butane. The mixture then flows into the heater 16.

The lead of the ignitor is positioned in the heater. With the spark of the ignitor (immediately following the start of gas flow) the gas ignites and heat starts conducting throughout the heater. Heat transfers to the cartridge by conduction, convection and/or radiation. The cartridge is shaped to fill the chamber, so as to maximize surface contact for thermal conduction.

As the cartridge heats, vapor generates within the cartridge and in the space immediately above it. When a user draws on the device, fresh air enters through air inlet 22, mixes with the vapor, and the mixture is delivered to the user via the inhalation passage 23. The air inlet or inlets can be directed downward, so as to improve the extraction of vapor from the cartridge. They can also be directed along a diagonal through the mouthpiece, or laterally through the case itself, above the cartridge.

FIG. 3 depicts a detailed view of the heater 16. The heater comprises a thermally conductive shell 26 and catalyst 27. The shell can be comprised of one material, or a combination of materials welded or pressed together. The catalyst can be platinum- or palladium-impregnated metal or glass, or other suitable material known to those skilled in the art. The catalyst provides for efficient flame-less combustion of

the butane. The vent 28 of the heater is positioned such that it is visible through the slot 29 of the body as shown in FIG. 1. This allows the user to see the catalyst which, when heated, can glow red to indicate that the device has been activated.

Referring again to FIG. 3, adjacent to the heater and in intimate thermal contact is the thermal regulator 17. As the temperature of the heater increases, so does that of the regulator. The regulator is designed to restrict the flow of butane as the temperature increases, thus creating a feedback loop. The regulator can consist of a bimetallic strip 60 and silicone tubing 61 which is the conduit of the butane. The two are arranged such that as the bimetallic strip heats up, it curls to pinch the silicone tube and thereby restrict the flow of butane. The reduced flow of butane results in less heat generated. The heater subsequently cools down, and so does the regulator, allowing more butane to flow again. The overall result is that a stable operating temperature is established in the heater. Such a system can be readily tuned to achieve an operating temperature that varies by less than +1-5 degrees Fahrenheit.

The regulator further comprises a moveable backplate 62 which allows adjustability of the operating temperature by adjusting the temperature at which the bimetallic actuator 25 closes the tube valve. This is to be performed once at manufacture, to calibrate the device. Alternatively, a control means may be used to allow the target temperature of the device changed during operation.

The regulator can comprise in part a bimetallic strip and 30 silicone tubing valve. Alternatively, the regulator can be comprised of other materials and configurations, as described later.

The desired operating temperature for vaporizing the smokeable materials herein can be below about 400 F. In 35 some cases, the operating range can be below about 350 F. For example, for the purposes of vaporizing most botanicals in this device, the desired operating temperature is below about 400 F, or, in some cases, below about 350 F.

The air inlet diameter can be sized such that inhalation is 40 somewhat inhibited. This allows time for ambient air entering the chamber to heat up and not affect operating temperature considerably. It also increases velocity of the entering air, which improves circulation and mixing in the vaporization chamber. It also creates a partial vacuum, 45 lowering the vapor point temperature for material contained in the vaporization chamber. The reduction in draw rate can also serve to give the impression of drawing on a cigarette or pipe. Both the fresh air inlet and inhalation passage can be adjusted to provide appropriate draw rate for the operating temperature of the device, and the perception intended for the user.

Once the cartridge is consumed, the device is turned off by pushing the tank back into the case, closing the master valve. The spent cartridge is removed by opening the device 55 and turning the body over. The cartridge can simply fall out. Alternatively, a mechanism can be used to quickly and easily remove the cartridge. This mechanism can include, but does not require, the use of a pin or slide part to eject the cartridge as another part of the device is moved or removed. The 60 removal mechanism can also involve introduction of a foreign object.

In some implementations, the mouthpiece may be permanently attached to the body. In that case, the vaporization chamber may be accessed by operating a sliding or hinged door, or similar means, built into the device.

The heater of the device is fitted into the case with an insulator 24. The insulator can be made of PEI (brand name

Ultem), ceramic, or other insulating material. The insulator serves to minimize thermal transfer from the heater to the case, while creating an air-tight seal. The seal prevents exhaust gases produced by the heater from entering the vaporization chamber. Exhaust gases are instead vented out the case slots. Since the air inlet is distant from the slots, there is substantially no contamination of the inhaled vapor mixture by heater exhaust gases.

In some implementations, the insulator can be a partially hollow shell, containing a sealed vacuum. In yet other implementations, the heater may be sealed directly to the case by braising in a vacuum furnace, so as to create a vacuum between the two and obviate need for an insulator component.

The tank can be made of a translucent material. This allows the user to determine the level of fuel remaining by looking at the base of the tank.

The case can be made of a material that is either a good thermal conductor (such as aluminum), or a poor one (such as ceramics). In both cases, the effect is that the body remains cool enough to touch over a large portion of its surface.

In one example, a bimetallic actuator can be used in the regulator. In another example, a shape memory alloy actuator such nickel-titanium alloys ("Nitinol") can be used. In yet another example, a paraffin-filled component that expands and contracts to modulate butane flow can be employed. In a further example, a system can be employed to measure the current temperature, e.g., with a thermocouple sensor and compare it to a prescribed temperature, e.g., with a micro-controller, and by controlling an electro-mechanical valve, e.g., servo or solenoid valve. In a configuration with user-selected temperature, as described above, the selected temperature can be used as an input to this system.

A thermal regulator may be used. Alternatively, the device may be constructed without an active regulating element. This may result in reduced complexity and in lowering the overall cost of the device. In this case, the flow of butane is set at a low level. In use, the temperature inside the chamber increases until an equilibrium point where additional heat introduced equals the heat lost to the environment. Heat is lost by conduction through the body of the device, and with the vapor delivered to the user. This equilibrium point determines the operating temperature of the device. By changing the butane flow rate, size and material of the burner, and other factors, the system can be calibrated to provide a fairly stable desired operating temperature.

An advantage of the bimetallic regulator feedback loop methods over the equilibrium method is that the operating temperature is not dependent on environmental factors such as ambient temperature and wind.

A piezo-electric ignitor can be used. Other ignitors may be used, such as, a flint starter or battery-powered resistive coil.

The butane tank may be refillable, and may have a port 25 for that purpose. Alternatively, the tank may be disposable once its fuel is exhausted. A release mechanism such as a pin or cam may be employed allowing the user to quickly remove the depleted tank and replace it with a full one. The replaceable tank may include additional parts of the device including, but not limited to, the ignitor and heater. Butane can be used as the fuel source, but may be replaced by other liquid fuels, such as ethanol.

Various means of feedback may be used to indicate the following states or metrics of the device: 1) the device is on, 2) the current temperature of the vaporization chamber, 3) the chamber is below a prescribed operating temperature, 4)

the chamber has reached a prescribed operating temperature and vapor is ready for consumption, and 5) the chamber has exceeded a prescribed operating temperature.

The means of the feedback includes both physical and electronic implementations. Possibilities include thermochromatic paint, light-emitting diodes and liquid crystal display. The sensing and control means for electronic feedback can be implemented by use of thermocouple and micro-controller, as is known to those skilled in the art.

10 The smokeable materials herein may include, but are not limited to, tobacco, botanicals (e.g., *cannabis*, chamomile), pharmaceuticals, nutraceuticals, natural or artificial flavorants, coffee grounds or coffee beans, mint, lemon, honey, tea leaves, cocoa, or any other substance providing a benefit or sensation to an end user.

15 The smokeable materials herein may be provided in loose leaf form, cut form, shredded form, chopped form, packed form, or any other natural or processed form. As described elsewhere herein, in some examples, the smokeable material 20 may comprise fine pieces of tobacco. In other examples, the smokeable material may comprise loose leaf tobacco. In yet other examples, the smokeable material may comprise loose leaf, shredded or chopped botanicals (e.g., loose leaves, shredded. The smokeable material comprise a vapor forming medium (e.g., glycerin).

25 Active elements contained in botanicals may vaporize at different temperatures. The device may be calibrated to establish a single stable temperature, intended for vaporizing solely tobacco or solely chamomile, for example. A control 30 means may be used to select a variety of temperature settings. The user may choose which setting based on the type of cartridge used. The control means can effect a desired temperature mechanically, such as by changing flow rate of the valve, or electronically, such as by electromechanical valve and micro-controller intermediary.

35 In some examples, butane may provide the most energy-dense and practical fuel source. In some examples, the butane heating system is replaced by a battery-powered electric heater or other compact heat source.

40 FIG. 4 depicts a cutaway view of a vaporization device which more closely resembles a traditional pipe form. In this configuration, the device retains all of the critical elements from the configuration in FIG. 1. The user inserts a cartridge 40, under a sliding top piece 41, where the cartridge mates 45 with the heater 42. Fuel held in the tank 43 is released by turning dial 44 to open master valve 45. The fuel travels through the regulator 51, and then through the carburetor 46 where it draws in air through the intake port 47 and catalyzes in a manner similar to that of the configuration in FIG. 1. As the cartridge 40 reaches its operating temperature the user places the mouthpiece 48 in their mouth and draws air in through the inhalation intake port 49 and through the vapor passage 50 where it is pre-cooled.

45 A cartridge comprising the smokeable material may be fitted in the device 10. The device can be configured to heat the smokeable material in the cartridge. The device can heat the smokeable material (e.g., in the vaporization chamber) to a temperature required to vaporize the smokeable material. The cartridge can be inserted into the heated vaporization 50 chamber of the device. For example, the device can heat the cartridge to below about 400 F. The cartridge may comprise a wrapper, a permeable pouch or a perforated container.

55 In some examples, the smokeable material (e.g., a moist smokeable material that may need to be contained in a wrapper) may be provided in a wrapper. The wrapper may be provided with a perforation that allows an exit of a vapor generated from heating the smokeable material. The perfor-

ration may further comprise an aeration well that allows air to access the smokeable material.

In some examples, the smokeable material (e.g., dry and/or loose smokeable material that may not need to be contained in a wrapper) may be provided in a permeable pouch. The pouch may be permeable to gases (e.g., air, vapor generated from heating the smokeable material, etc.). The permeable pouch may allow air to access the smokeable material. The permeable pouch may allow an exit of a vapor generated from heating the smokeable material. The permeable pouch may eliminate the need to directly expose the smokeable material to the surroundings (e.g., by leaving a portion of the smokeable material exposed, as shown, for example, in FIG. 7, or by providing perforations, in some cases together with aeration wells, that allow vapor to exit and/or air to enter, as shown, for example, in FIGS. 5, 6 and 8). The permeable pouch may eliminate the need to puncture the cartridge. The permeable pouch may be permeable on all surfaces. All surfaces of the permeable pouch may be permeable. The permeable pouch may comprise one or more permeable surfaces. Further, the permeable pouch may enhance air and vapor transport to and from the smokeable material (e.g., by providing air and vapor transfer across a larger surface of the pouch as compared to the vapor transfer available in a cartridge that only has a single or more than one perforations on one or two sides).

In some examples, the smokeable material (e.g., dry and/or loose smokeable material that may not need to be contained in a wrapper) may be provided in a perforated container. The perforated container may comprise or be formed of a metallic foil (e.g. aluminum, stainless steel, or copper) with a perforation pattern to allow gas transfer through the container. The perforated container may have a perforation pattern on at least one surface of the container. The perforated container may allow air to access the smokeable material. The perforated container may allow an exit of a vapor generated from heating the smokeable material. The perforated container may eliminate the need to directly expose the smokeable material to the surroundings. The perforated container may eliminate the need to puncture the cartridge. Further, the perforated container may enhance air and vapor transport to and from the smokeable material (e.g., by providing air and vapor transfer across a larger surface). The perforated container may comprise or be formed of a thermally conductive material to enhance heat transfer to the smokeable material. The perforated container may be perforated on all surfaces. All surfaces of the perforated container may comprise perforations. The perforated container may comprise one or more perforated surfaces. Further, the perforated container may enhance air and vapor transport to and from the smokeable material (e.g., by providing air and vapor transfer across a larger surface of the container as compared to the vapor transfer available in a cartridge that only has a single or more than one perforations on one side or only on two opposing sides).

Any aspects of the disclosure described in relation to a cartridge comprising a wrapper may equally apply to cartridges comprising a permeable pouch or a perforated container at least in some configurations. Any aspects of the disclosure described in relation to a cartridge comprising a permeable pouch may equally apply to cartridges comprising a wrapper or a perforated container at least in some configurations. Any aspects of the disclosure described in relation to a cartridge comprising a perforated container may equally apply to cartridges comprising or a wrapper or a permeable pouch at least in some configurations.

FIG. 5 depicts a sectional view of an example of a cartridge 30. The cartridge consists of a smokeable material 31, enclosed in a wrapper 32, with perforations 33, and aeration wells 34. The wrapped cartridge allows for the easy insertion and disposal of smokeable material (e.g., tobacco material, botanicals, or any other smokeable material herein) without creating a mess, while the perforations allow the formed vapor to be released. When the cartridge is used up it can be easily disposed of in its entirety.

10 Smokeable material, such as, for example, tobacco or tobacco material, may be any combination of natural and synthetic material that can be vaporized for pleasure or medicinal use. In an example, a test cartridge is prepared using flue-cured tobacco, glycerin, and flavorings. Those skilled in the art of tobacco product manufacture are familiar with these and other ingredients used for cigarettes, cigars, and the like. The cartridge is produced by chopping tobacco into fine pieces (less than 3 mm diameter, preferably less than 2 mm; having no dimension larger than 3 mm, or having substantially all fine pieces be less than 2 mm in all dimensions), adding the other ingredients, and mixing until even consistency is achieved.

15 The cartridge may be substantially cylindrical. In other implementations, the form can be modified for various reasons. As an example, the walls of the cartridge may be drafted for easier insertion into the vaporization chamber. Or, the bottom of the cartridge may possess receptacles, which when combined with complimentary features on the surface cavity of the vaporization chamber may allow for 20 more surface contact and hence improved thermal conduction. The wrapper may be formed as a pouch in some implementations.

25 Any material may be used for the wrapper, provided that when heated to the operating temperature, it does not produce significant amounts of harmful gases. Aluminum foil and parchment paper are two examples. With papers, the cartridge may be manufactured in a folded-cup design, similar to that shown in FIG. 6. With films or metal foils, the wrapper can be pressed or blow-molded to the appropriate 30 shape.

35 During manufacture, the cartridge may be enclosed on all sides, and perforated on the top so that vapors can emanate upwards. In the perforation step, or in an additional step, the optional aeration wells may be created.

40 The cartridge may be wrapped on all sides but leaving the top exposed, as shown in FIG. 7. This is possible since the purpose of the wrapper is primarily to prevent tobacco material from touching the sides and bottom of the vaporization chamber.

45 In another implementation, the material for the top of the cartridge may be vapor permeable, such that perforations are not necessary. As described in greater detail elsewhere herein, cartridges of the disclosure may also be air permeable. Such air and vapor permeable cartridges may advantageously be used to enhance air and vapor transfer along one, two or more (or all) surfaces of the cartridge.

50 In another implementation, the cartridge as purchased by the user has no openings, but is punctured prior to insertion into the device, or upon introduction to the vaporization device. The latter can be achieved by adding a hollow puncturing means to the mouthpiece part of the device. For example, the inhalation passage of the mouthpiece can be extended by a hollow tube. When the mouthpiece is reinserted to close the device, it pierces the cartridge previously 55 introduced, and allows a path for vapor to exit to the user.

56 In some examples, the tobacco material may be a homogeneous mixture. In other examples, there may be two layers,

as shown in FIG. 8. The moist layer 35 has higher content of vapor-forming material than the dry layer 36, which consists of dry tobacco or other material acting as a filter. The dry layer serves to prevent any liquid from bubbling up and out of the cartridge during heating.

In some examples, a lower compartment may consist entirely of a vapor-forming medium, such as glycerin. An upper region may consist of the tobacco material to be vaporized, and the two may be separated by a material that only allows the medium to pass in a vapor or gaseous phase. Gore-tex (brand name) is one such material. In use, vapor generated in the lower region may pass through the semi-permeable membrane, volatize the active components of the tobacco, and a mix of the two may be delivered to the user upon inhalation.

In some implementations, the consistency of the tobacco material is such that the wrapper is not necessary. This is possible if at least the outer surface of the cartridge is dry and cohesive enough to not leave deposits inside the device. Such a cartridge can be made by forming tobacco material in a mold. If the resulting surface is excessively moist, it can be dried by heating the cartridge in an oven.

The cartridge 30 may comprise a permeable pouch containing a smokeable material. The permeable pouch may comprise cellulose and/or other permeable materials (e.g., other fibers) capable of withstanding the operating temperatures of the device. The permeable pouch may comprise a binding agent or binder (e.g., cellulose acetate fibers). The binding agent or binder may be capable of withstanding the operating temperatures of the device (e.g., during heating of the smokeable material in the permeable pouch) without vaporizing ("off-gassing"). The binding agent may be safe for inhalation by a user. Thus, the permeable pouch may be capable of withstanding the operating temperatures of the device (e.g., during heating of the smokeable material in the permeable pouch) while remaining intact. The permeable pouch may be heat-sealed (e.g., at a temperature of about or exceeding the operating temperature of the device). The permeable pouch may be permeable to air, and/or vapor (e.g., vapor generated from heating the smokeable material). The permeable pouch may contain a given quantity of smokeable material. The given quantity of smokeable material may be chosen based on device dimensions, duration of smoking time, or desired smoke or vapor composition.

The cartridge 30 may comprise a perforated container containing a smokeable material. The perforated container may comprise a metallic foil with a perforation pattern on at least one surface. The perforated container may be welded shut or the perforated container may comprise a binding agent or binder (e.g., cellulose acetate fibers). The binding agent or binder may be capable of withstanding the operating temperatures of the device (e.g., during heating of the smokeable material in the perforated container) without vaporizing ("off-gassing"). The binding agent may be safe for inhalation by a user. Thus, the perforated container may be capable of withstanding the operating temperatures of the device (e.g., during heating of the smokeable material in the perforated container) while remaining intact. The perforated container may be heat-sealed (e.g., at a temperature of about or exceeding the operating temperature of the device) or welded. The perforated container may allow passage to air, and/or vapor (e.g., vapor generated from heating the smokeable material). The perforated container may contain a given quantity of smokeable material. The given quantity of smokeable material may be chosen based on device dimensions, duration of smoking time, or desired smoke or vapor

composition. The perforated container may be formed as a pouch in some implementations.

FIG. 9 is an example of a pouch 906 containing a smokeable material, fitted in a vaporization device 900. In 5 this example, the device comprises a body 901. The device may comprise a mouthpiece 902 with an aerosol outlet 922, a condenser 903, a heater 905, and an oven or vaporization region 904. The oven region 904 may comprise an oven or vaporization chamber 907. Air may be drawn into the device 10 through the air inlet 921 by a user puffing on the mouth piece. The pouch 906 may be placed in the oven region 904, where it may be heated by the heater 905 to generate a vapor or aerosols of the smokeable material. The pouch may comprise a permeable material or a thermally conductive material with a perforation pattern. Permeability of the 15 pouch by means of composition of a permeable material or perforations may improve heat and mass transfer to the smokeable material in the pouch (e.g., eliminate the need for aeration vents in the oven region 904).

FIG. 10 shows an example of an oven region 1000 of a 20 device. The oven region may comprise an oven chamber 1007 designed to fit a cartridge comprising a pouch (e.g., a permeable pouch). The pouch may comprise a permeable material or a thermally conductive material with a perforation pattern. The oven chamber may have a lid 1030 so that the user may access the oven region to insert and remove cartridges. Air may be drawn in to the oven region through an inlet 1021 and exit the oven region through an outlet 1022. Vapor generated from the heating of the smokeable 25 material in the pouch may exit the oven region through an outlet 1022. The air may mix with vapor generated from the heating of the smokeable material. The mixing may take place in the oven chamber 1007, and the combined gas stream may exit through the outlet 1022. Permeability of the 30 pouch by means of composition of a permeable material or perforations may improve heat and mass transfer to the smokeable material in the pouch (e.g., eliminate the need for aeration vents in the oven region 1000).

40 In some implementations, devices comprising a vaporization chamber configured to fit a pouch (e.g., as shown in FIGS. 9 and 10) may advantageously be used with a pouch that is permeable all around. In some examples, more efficient vapor removal may be achieved with an air path that traverses the pouch, as shown in FIGS. 9 and 10. In some 45 implementations, greater flexibility for the device design may be realized as a result of improved air flow and vapor removal. For one example, the air inlet 22 in FIG. 2 may be provided on the mouthpiece 11 in an alternative configuration. In another example, the air inlet may be configured 50 separately from the mouthpiece, as shown, for example, in FIG. 9.

55 It is to be understood that the terminology used herein is used for the purpose of describing specific embodiments, and is not intended to limit the scope of the present invention. It should be noted that as used herein, the singular forms of "a", "an" and "the" include plural references unless the context clearly dictates otherwise. In addition, unless defined otherwise, all technical and scientific terms used herein have the same meaning as commonly understood by one of ordinary skill in the art to which this invention belongs.

60 While preferable embodiments of the present invention have been shown and described herein, it will be obvious to those skilled in the art that such embodiments are provided by way of example only. Numerous variations, changes, and substitutions will now occur to those skilled in the art without departing from the invention. It should be under-

11

stood that various alternatives to the embodiments of the invention described herein may be employed in practicing the invention. It is intended that the following claims define the scope of the invention and that methods and structures within the scope of these claims and their equivalents be covered thereby.

What is claimed is:

1. An apparatus comprising:

a cartridge comprising a perforated container containing a vaporizable material, the perforated container having two or more perforated surfaces configured to allow gas transfer through the perforated container between the two or more perforated surfaces, the gas transfer comprising entry of air into the perforated container and exit of the air and a vapor generated by heating the vaporizable material; and

a device comprising:

an oven region comprising an oven chamber configured to surround the perforated container and heat the vaporizable material in the perforated container;

an air inlet through which air is drawn into the oven region;

an airflow path that traverses the perforated container between the two or more perforated surfaces; and

a mouthpiece comprising an aerosol outlet configured to deliver, to a user puffing on the mouthpiece, a mixture of the air and the vapor generated by heating the vaporizable material, the air and the vapor generated by heating the vaporizable material being mixed in the oven chamber before exiting the oven region.

2. The apparatus of claim 1, wherein the perforated container comprises cellulose.

3. The apparatus of claim 1, wherein the perforated container is configured to remain substantially intact during the heating of the vaporizable material in the perforated container.

4. The apparatus of claim 1, wherein the perforated container comprises a binding agent.

5. The apparatus of claim 4, wherein the binding agent is configured to remain substantially intact during the heating of the vaporizable material in the perforated container.

6. The apparatus of claim 1, wherein the perforated container is heat-sealed.

7. The apparatus of claim 1, wherein the vaporizable material comprises a vapor forming medium.

8. The apparatus of claim 7, wherein the vapor forming medium comprises glycerin.

9. The apparatus of claim 1, wherein the device is configured to heat the vaporizable material to a temperature required to vaporize the vaporizable material.

10. The apparatus of claim 1, wherein the device is configured to heat the cartridge to a temperature below about 400° F.

11. The apparatus of claim 1, wherein the vaporizable material comprises tobacco.

12. The apparatus of claim 1, wherein the vaporizable material comprises botanicals.

13. The apparatus of claim 12, wherein the vaporizable material comprises *cannabis*.

14. The apparatus of claim 1, wherein the vaporizable material comprises fine pieces of the vaporizable material.

15. The apparatus of claim 1, wherein the vaporizable material comprises loose leaves of the vaporizable material.

16. The apparatus of claim 1, wherein the perforated container encloses the vaporizable material on all surfaces of the vaporizable material.

12

17. The apparatus of claim 1, wherein the two or more perforated surfaces are on different sides of the perforated container.

18. The apparatus of claim 1, wherein the perforated container comprises a permeable material comprising fibers.

19. The apparatus of claim 1, wherein the perforated container comprises cellulose acetate fibers.

20. The apparatus of claim 1, further comprising a battery-powered electric heater.

21. The apparatus of claim 1, wherein the oven chamber includes a lid to access the oven chamber to insert and remove the perforated container.

22. The apparatus of claim 21, wherein the lid comprises the mouthpiece.

23. The apparatus of claim 1, wherein the perforated container further comprises at least one aeration well, the at least one aeration well and the perforations together allowing the air to enter the perforated container and the air and vapor generated by heating the vaporizable material to exit the perforated container.

24. The apparatus of claim 1, wherein the perforated container is pre-perforated with the perforations prior to use such that the perforated container does not require being punctured during use.

25. The apparatus of claim 1, further comprising a condenser.

26. The apparatus of claim 1, wherein the perforated container is welded shut.

27. A cartridge configured for use in a vaporizer device comprising an oven chamber, the cartridge comprising:

a perforated container having two or more perforated surfaces; and
a vaporizable material within the perforated container; wherein the perforations allow gas transfer that traverses the perforated container between the two or more perforated surfaces, the gas transfer comprising entry of air into the perforated container and exit of the air and a vapor generated by heating the vaporizable material when the cartridge is placed in the oven chamber.

28. The cartridge of claim 27, wherein the perforated container is pre-perforated with the perforations such that the perforated container does not require being punctured during use.

29. The cartridge of claim 27, wherein the vaporizable material comprises tobacco.

30. The cartridge of claim 27, wherein the perforated container is welded shut, heat-sealed, or sealed with a binding agent.

31. A device for use with a cartridge comprising a perforated container containing a tobacco material, the perforated container having two or more perforated surfaces, the device comprising:

an oven region comprising an oven chamber configured to surround the perforated container and heat the vaporizable material in the perforated container;
an air inlet through which air is drawn into the oven region;
an airflow path via which the air traverses the perforated container between the two or more perforated surfaces;
a condenser; and
a lid to access the oven chamber to insert and remove the perforated container, the lid comprising a mouthpiece comprising an aerosol outlet configured to deliver, to a user puffing on the mouthpiece, a mixture of the air and the vapor generated by heating the vaporizable material, the air and the vapor generated by heating the

vaporizable material being mixed in the oven chamber before exiting the oven region.

32. The device of claim **31**, wherein the two or more perforated surfaces are on different sides of the perforated container. 5

33. The cartridge of claim **27**, wherein the two or more perforated surfaces are on different sides of the perforated container.
